HAND TOOL FOR GARMENT CONDITIONING

David A. Martin, 2375 Colgate Drive,
Costa Mesa, Calif.

Filed Feb. 3, 1964, Ser. No. 78,500

Term of patent 14 years

(Cl. D9—2)

Fig. 1.

Fig. 2.

Fig. 3.

FIG. 1 is a perspective view of a hand tool for garment conditioning, showing my new design;

FIG. 2 is an elevational view of the side of the tool not shown in FIG. 1; and

FIG. 3 is a bottom view thereof.

The stippled portions of FIGS. 1 and 2 are intended to represent conventional abrasive material.

I claim:

The ornamental design for a hand tool for garment conditioning, as shown and described.
